CAN OPENING PUNCH DEVICE

Robert W. Heaviside, Falls Church, Va.

Application November 3, 1954, Serial No. 466,521

13 Claims. (Cl. 30—6.1)

This invention relates to a can opening device and more specifically provides a device for punching holes in the top of a can such as those containing liquids or semi-liquids and which may be attached to a convenient supporting wall or similar type support.

An object of this invention is to provide a can opening punch device which will simultaneously and automatically punch two holes or openings in the top of a can in a single operation.

Another object of the present invention is to provide a can opening punch device that will simultaneously punch two holes in the top of a can when a can is positioned in the correct manner in the can punching device and then pushed inwardly wherein the device of the present invention will raise the can into contact with the punch devices thereby puncturing the top of the can.

Yet another important object of the present invention is to provide a can opening device conformable to the preceding objects which includes means for automatically disengaging the can from the can opening device thereby permitting the punctured can to be easily removed from the can opening device by a simple downward movement thereby eliminating wastage due to spilling.

A still further important object of the present invention is to provide a can opening device in accordance with the several preceding objects in which the distance between the punching devices may be adjusted and the vertical height of the punching devices may be adjustable thereby forming the can opening device that is adjustable for various sizes of cans regardless of length or diameter.

Yet another important feature of the present invention is to provide a can opening device that is normally in can receiving position but which may be collapsed to an out-of-the-way position closely adjacent the surface of the support.

Other important objects of the present invention will reside in the simplicity of construction, ease of operation, efficiency, ease of cleaning, universally adapted to various sizes of cans, its adaptation for its various purposes and its relatively inexpensive manufacturing cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view showing the can opening punch device of the present invention in its collapsed condition;

Figure 2 is a longitudinal, vertical sectional view taken substantially upon a plane passing through the longitudinal center line thereof showing the can opening device of the present invention in can receiving position;

Figure 3 is a longitudinal, vertical sectional view similar to Figure 2 showing the can opening device of the present invention in operation wherein the can positioned therein has been punctured and removed from the can holding member for disengagement from the can opening device;

2

Figure 4 is a longitudinal, vertical sectional view taken substantially upon the plane passing along section line 4—4 of Figure 1 showing structural details of the device of the present invention when in its collapsed condition;

Figure 5 is a group perspective view showing the laterally projecting arm that is pivotally and vertically mounted on a pivotal member for supporting the punch members;

Figure 6 is a detailed perspective view showing the lower end of the laterally projecting arm and especially illustrating the recess for receiving a hook for holding the arm in collapsed position;

Figure 7 is a group perspective view showing the manually actuating latch for holding the pivotal member in collapsed position alongside the forward surface of the mounting bracket;

Figure 8 is a detail sectional view showing the construction of the resilient spring for urging the pivotal member outwardly into a depending angular relation to the supporting bracket;

Figure 9 is a longitudinal, vertical sectional view taken substantially upon a plane passing along the longitudinal center line of a modified and simplified form of the can opening device of the present invention;

Figure 10 is a vertical sectional view similar to Figure 9 showing the device of this form of the invention in can opening condition similar to the position as illustrated in Figure 3;

Figure 11 is a perspective view showing the details of construction of the can opening punch device wherein the punching members are rigidly secured to a pivotal member; and

Figure 12 is a top plan sectional view taken substantially upon a plane passing along section line 12—12 of Figure 10 showing the details of construction of the pivotal member and the sliding can holding member together with the relationship between the can engaging ledge and the projecting means for disengaging the can from such ledge.

Referring now specifically to Figures 1—8 of the official drawings, it will be seen that the numeral 10 generally designates the form of the can opening device of the present invention illustrated therein. The can opening device 10 includes a generally vertically elongated bracket 12 having a peripheral flange 14 with a plurality of tubular studs or bosses 16 extending from a front plate 18 to a position in planar relation to the flange 14 wherein fastening members such as screws may be utilized for attaching the device 10 through a supporting wall 20 or other similar type of supports whereby the bracket 12 is disposed in a vertical position.

The front plate 18 is provided with a centrally disposed recess 22 formed by a peripheral wall 24 for a purpose described hereinafter. Projecting forwardly from the front plate 18 is a pair of side flanges 26 and a bottom flange 28 interconnecting the bottom of the side flanges 26. The side flanges 26 and the bottom flange 28 are spaced inwardly and are confined by the peripheral flange 14. Pivotally connected adjacent the upper end of the side flanges 26 is a pivotal member generally indicated by the numeral 30 that is connected to the side flanges 26 by a pivot pin 32. The pivotal member 30 is generally elongated and is normally disposed in a depending angular relation to the bracket 12 wherein the pivotal member 30 may be moved from a position illustrated in Figure 2 to a position as illustrated in Figure 3.

An axial coil spring 34 provided with extending end members 36 and 38 is provided in surrounding relation to the pivot pin 32 and the end 36 engages the front plate 18 and the end 38 engages the recess 40 in the rear surface of the pivotal member 30 thereby normally urging the pivotal member 30 outwardly into an angular rela-

tion to the supporting bracket 12 as illustrated in Figure 2 and shown specifically in Figure 8.

The elongated pivotal member 30 includes a generally channel shaped member 42 having inwardly extending upper edges 44 which project over the inner edges of the channel shaped member 42 thereby forming a guide channel for slidably receiving a lug 46 having a pivot lug 48 on the forward surface thereof. The upper end of lug 46 is provided with projections 50 adjacent each side thereof for a purpose described hereinafter. Pivoted secured to the pivot lug 48 by a pivot pin 52 is a laterally projecting arm 54 having pivot lugs 56 thereon for positioning over the pivot lug 48 and receiving the pivot pin 52 thereby pivotally securing the arm 54 to the mounting lug 46. Rigidly secured to the undersurface of the arm 54 adjacent the inner end thereof is a generally triangular solid punch member 58 having a grooved flat inner surface 60. The arm 54 is generally in construction thereby forming a longitudinal guide 62 for slidably receiving the polygonal head 64 of a depending circular punch 66 having a sharpened lower end 68 wherein the punch 66 in coaction with the punch 58 will simultaneously punch two holes in a can 70 when the can 70 is raised into engagement therewith. The inner end of the arm 54 is provided with an upwardly and inwardly tapered end 72 for engagement with one of a series of vertically spaced recesses or notches 74 on the forward surface of the channel-shaped member 42. Also positioned alongside the extending arm 54 is a pointer 76 which coacts with indicia 78 on the surface of one of the inturned edges 44 for determining the vertical position of the laterally extending arm 54. An axial spring 80 is provided around the pivot pin 52 and includes one end portion 82 which engages against the front surface of the mounting lug 46 and free end member 84 which engages against the undersurface of the laterally extending arm 54 wherein in the arm 54 will be urged outwardly to a perpendicular position in relation to the pivotal member 30. Adjacent the outer end of the arm 54 is provided a small notch 86 for a purpose described hereinafter. Immediately below the portion of the channel-shaped member 42 having the notches 74 therein is an elongated slot 88 and positioned between the edges of the slot 88 and the edge members 44 is a can holding member generally designated by the numeral 90 and including a sliding plate 92 that is provided with a rearwardly projecting pivot lug 94 on its upper end that is pivotally connected by pivot pin 96 to an interconnecting link 98 pivotally secured to pivot lugs 100 by a pivot pin 102 at the bottom end of the plate 18. The bottom of the plate 92 rests against the inner surface of the pivotal member 30 when in its lowermost position and includes a projecting ledge 104 for engaging the bottom of a can 70. Adjacent the upper surface of the ledge 104 is a centrally disposed opening 106 for receiving and permitting passage of a projection 108 on the forward surface of the interconnecting link 98 wherein the projection 108 will pass through the opening 106 and engage the periphery of the can 70 adjacent the ledge 104 thereby urging the can 70 off of the ledge 104 as illustrated in Figure 3 for disengaging the can 70 from the can opening device 10. The projection 108 may be provided with a concave forward surface for generally conforming to the contour of the can 70. On the outer surface of the plate 92 adjacent the central portion thereof is a forwardly and upwardly projecting hook member 110 which is provided with a projection substantially equal in size to the notch 86 in the arm 54 wherein the hook 110 will engage in the notch 86 when the arm 54 is pivoted downwardly alongside the channel member 42.

Referring now specifically to Figure 7, it will be seen that the outer edge of the channel shaped member 42 is provided with a recessed portion 112 having a vertically extending notch 114 for receiving a slide latch 116 that is vertically slidable in a groove 116 and includes an actuating handle member 118 which

projects outwardly from the side flange 26 for securing the pivotal member 30 alongside the front surface of the plate 18 so that the can opening device of the present invention may be held in collapsed position.

In practical use of the present invention, the can opening device 10 is attached to a suitable supporting wall or other supporting structure 20 with pivotal member 30 in normally angular relation and the laterally extending arm 54 in perpendicular relation to the pivotal member 30. A can 70 is positioned with the bottom thereon on the ledge 104 and the can 70 is pushed inwardly thereby pivoting the pivotal member 30 about the pivot pin 32 so that it moves toward the front surface of the bracket 12. By pivoting the arm 54 downwardly and sliding the mounting of the sliding lug 46 vertically, the pin portion 72 of the arm 54 may be positioned in any of the selective notches 74 thereby vertically adjusting the arm 54 for accommodating cans of various heights or lengths. By adjusting the pointed punch 66 in the guide 62, the distance between the punches 58 and 66 may be adjusted thereby accommodating cans of various diameters. As the can 70 along with the pivotal member 30 is moved inwardly, the interconnecting link 98 moving about its pivotal connection 96 and 102 will move the sliding plate 92, the ledge 104 and the can 70 upwardly and longitudinally along the pivotal member 30 until they contact and pass over and onto the punch members 58 and 66 thereby punching two diametrically opposed holes in the upper end of the can 70. As the can 70 and the pivotal member 30 moves to inner limit of movement, the projection 108 passes through the opening 106 in the plate 92 and engages the periphery of the can 70 adjacent the lower end thereof thereby removing the lower end of the can 70 from the ledge 104 for permitting the can 70 to be pulled downwardly off of the punch members 58 and 66 thereby forming an easily operating can opening device.

When it is desired to collapse the can opening device 10 of the present invention to an out-of-the-way position, the punch member 66 is moved inwardly to its inner limit of movement and the arm 54 pivoted downwardly so that the punch members 58 and 66 will pass through the enlarged slot 88 and be positioned in the recessed portion 22 of the front face 18. After the arm 54 has been pivoted downwardly, the pivotal member 30 is pivoted inwardly wherein the plate 92 will slide upwardly for engaging the hook 110 with the notch 86 in the outer end of the arm 54 thereby automatically locking the arm 54 to the pivotal member 30. After the pivotal member 30 is moved to its innermost position, the manual latch 116 is moved upwardly into the notch 114 in the outer surface of the channel shaped member 42 by utilizing the handle member 118 thereby securely positioning the pivotal member 30 and the arm 54 in collapsed position. When it is desired to extend the can opening device 10, the handle 118 is manually moved downwardly wherein the spring 34 will pivot the pivotal member 30 outwardly and the spring 80 will automatically pivot the arm 54 to a perpendicular relation thereby automatically extending the arm 54 to its operating position and the can opening device 10 is then ready for use. It will be seen that the device of the present invention is especially useful in opening a plurality of cans that contain liquids or semi-liquids wherein it is only necessary to punch a pair of diametrically opposed holes in the top thereof.

Referring now specifically to Figures 9-12, it will be seen that the numeral 120 generally indicates the modified and simplified form of the can opener of the present invention. The form of the invention as illustrated in Figures 9-12 includes a flat supporting bracket 122 having apertures 124 therein for receiving mounting screws. At the upper end of the bracket 122 is pivotally mounted a channel shaped pivotal member 126 by pivot pin 128. An axial spring 130 surrounds the pivot pin 128 and is disposed with one end against the forward surface of the

bracket 122 and one end against the rear surface of the channel shaped pivotal member 126 thereby urging the channel shaped pivotal member 126 outwardly to a normally depending angular relation to the vertically disposed bracket 122. Rigidly secured to the upper end and projecting laterally outwardly therefrom is an arm 132 having a depending angulated punch member 134 on the outer end thereof and a depending generally triangular punch member 136 on the inner end thereof having a flat face 138 for punching two diametrically opposed openings in the top of a can 140. The lower end of the channel shaped member 126 is provided with an elongated and enlarged slot 142 for slidably receiving a plate 146 having inwardly extending grooves 148 in the opposite longitudinal edges thereof wherein the grooves 148 slidably receive the portions of the channel shaped member 126 which forms the edges of the slot 142, thereby slidably guiding the plate 146 on the pivotal member 126. The lower end of the plate 146 is provided with an inwardly extending ledge 150 for engaging under the bottom of the can 140. The upper end of the plate 146 is pivotally connected to an interconnecting link 152 by pivot pin 154 and the other end of the link 152 is connected adjacent the bottom of the bracket 122 by pivot pin 156. It will be seen that by inward pivotal movement of the pivotal member 126, the plate or can holding member 146 will be moved longitudinally in relation to the pivotal member 126 thereby moving the can holding ledge 150 towards the punch members 136 and 134 for punching diametrically opposed holes in the top of the can 140 when the pivotal member 126 is urged inwardly. It will be noted that the forward surface of the bracket 122 is provided with pivot lugs 158 on opposite edges thereof for receiving the pivot pin 156 which extends through the bottom end of the interconnecting link 152. Secured to and integrally formed with the interconnecting link 152 is a pair of outwardly or forwardly projecting legs 160 which bridge each side of the channel shaped pivotal member 126 for engaging the periphery of the can 140 adjacent the pivotal member 126 and adjacent the ledge 150 when the pivotal member 126 and the can 140 are moved inwardly substantially alongside and coextensive to the bracket 122. The operation of this form of the invention is the same as that form illustrated in Figures 1-8 and is substantially the same except that it is formed in a more simplified nature thereby reducing the manufacturing cost to an absolute minimum.

In both forms of the invention, the can to be opened is merely positioned on a can supporting ledge 104 or 150 and the can pivoted inwardly along with the pivotal members 30 or 126 thereby engaging the top of the can onto the punch members 66, 58 or 134, 136, thereby punching diametrically opposed holes in the top of the can. After each operation, the can opening device 10 or 120 returns to its normal can receiving position wherein another can may be easily inserted therein for opening. Also, the projection 103 or the projecting leg 160 will quickly disengage the can from the can engaging ledge 104 or 150 thereby permitting easy and rapid removal of the can from the can opening device 10 or 120. In each case, the device represents an easily and efficiently used can opening device wherein a person opening a can may do so utilizing only one hand while the other hand holds another can to be opened or for performing any other function. The device is especially useful in opening cans of liquid wherein a plurality of cans must be opened in a relatively short time such as in places serving the public liquids of any nature that are normally packaged and delivered in cans or similar containers. Obviously, the device may be constructed of any suitable material that is attractive for use in homes, restaurants, bars or the like, and which will be relatively light and inexpensive wherein the device may be constructed utilizing well known manufacturing procedures thereby holding the manufacturing and

resultant sale price to a minimum. It will be noted that the groove in the punch members 58 and 136 permit escape of air from the can as it is being punched thereby preventing the liquid from spouting out as the punches are pressed into the can.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

15. What is claimed as new is as follows:

1. A can opening device comprising a supporting bracket adapted to be attached to a support, a member pivotally secured to said bracket adjacent one end thereof, a can holding member slidably mounted on said pivotal member, a can opening punch mounted in alignment with said can holding member, means for sliding said can holding member longitudinally along said pivotal member thereby urging a can on the can holding member towards said punch.

2. A can opening device comprising a supporting bracket adapted to be attached to a support, a member pivotally secured to said bracket adjacent one end thereof, a can holding member slidably mounted on said pivotal member, a can opening punch mounted in alignment with said can holding member, means for sliding said can holding member longitudinally along said pivotal member thereby urging a can on the can holding member towards said punch, and means for urging a can away from the can holding member when the can is urged onto the punch.

3. A can opening device comprising a supporting bracket adapted to be attached to a support, a member pivotally secured to said bracket adjacent one end thereof, a can holding member slidably mounted on said pivotal member, a can opening punch mounted in alignment with said can holding member, means for sliding said can holding member longitudinally along said pivotal member thereby urging a can on the can holding member towards said punch, and means for urging a can away from the can holding member when the can is urged onto the punch, said can holding member including a projecting ledge for engaging one end of a can.

4. A can opening device comprising a supporting bracket adapted to be attached to a support, a member pivotally secured to said bracket adjacent one end thereof, a can holding member slidably mounted on said pivotal member, a can opening punch mounted in alignment with said can holding member, means for sliding said can holding member longitudinally along said pivotal member thereby urging a can on the can holding member towards said punch, said can opening punch including a pair of laterally spaced projecting pointed members for simultaneously punching two holes in the end of a can adjacent opposite sides thereof.

5. A can opening device comprising a supporting bracket adapted to be attached to a support, a member pivotally secured to said bracket adjacent one end thereof, a can holding member slidably mounted on said pivotal member, a can opening punch mounted in alignment with said can holding member, means for sliding said can holding member longitudinally along said pivotal member thereby urging a can on the can holding member towards said punch, said can holding member sliding means including a rigid link pivotally interconnecting the can holding member and the supporting bracket wherein the can holding member will move longitudinally of the pivotal member as the pivotal member is moved about its pivotal connection to the supporting bracket.

6. A can opening device comprising an elongated vertically disposed supporting bracket for attachment to a

support, an elongated pivotal member attached to the upper end of said bracket and normally depending therefrom in coextensive angular relation, a laterally extending arm on said pivotal member, a pair of spaced depending punch members on said arm, a can holding member slidably mounted on said pivotal member below the punch members, a projecting ledge on the slidable member for engaging the bottom of a can, a connecting link pivotally interconnecting the upper end of the sliding member and the lower end of the bracket for moving the sliding member longitudinally of the pivotal member when the pivotal member is moved about its pivotal connection to the bracket thereby raising a can positioned on said ledge into contact with the punch members for puncturing a pair of spaced holes in the top of the can, and projecting means for engaging the side wall of a can when it has been punctured for disengaging the bottom of the can from the ledge thereby permitting removal of the can.

7. A can opening device comprising an elongated vertically disposed supporting bracket for attachment to a support, an elongated pivotal member attached to the upper end of said bracket and normally depending therefrom in coextensive angular relation, a laterally extending arm on said pivotal member, a pair of spaced depending punch members on said arm, a can holding member slidably mounted on said pivotal member below the punch members, a projecting ledge on the slidable member for engaging the bottom of a can, a connecting link pivotally interconnecting the upper end of the sliding member and the lower end of the bracket for moving the sliding member longitudinally of the pivotal member when the pivotal member is moved about its pivotal connection to the bracket thereby raising a can positioned on said ledge into contact with the punch members for puncturing a pair of spaced holes in the top of the can, and projecting means for engaging the side wall of a can when it has been punctured for disengaging the bottom of the can from the ledge thereby permitting removal of the can, said projecting means positioned on said interconnecting link and being of a length to project beyond the ledge when the pivotal member is moved inwardly into parallel relation to the bracket.

8. A can opening device comprising an elongated vertically disposed supporting bracket for attachment to a support, an elongated pivotal member attached to the upper end of said bracket and normally depending therefrom in coextensive angular relation, a laterally extending arm on said pivotal member, a pair of spaced depending punch members on said arm, a can holding member slidably mounted on said pivotal member below the punch members, a projecting ledge on the slidable member for engaging the bottom of a can, a connecting link pivotally interconnecting the upper end of the sliding member and the lower end of the bracket for moving the sliding member longitudinally of the pivotal member when the pivotal member is moved about its pivotal connection to the bracket thereby raising a can positioned on said ledge into contact with the punch members for puncturing a pair of spaced holes in the top of the can, and projecting means for engaging the side wall of a can when it has been punctured for disengaging the bottom of the can from the ledge thereby permitting removal of the can, said connection between the bracket and pivotal member including resilient means normally urging the pivotal member outwardly into a can receiving angular relation to the bracket.

9. A can opening device comprising an elongated vertically disposed supporting bracket for attachment to a support, an elongated pivotal member attached to the upper end of said bracket and normally depending therefrom in coextensive angular relation, a laterally extending arm on said pivotal member, a pair of spaced depending punch members on said arm, a can holding member slidably mounted on said pivotal member below

the punch members, a projecting ledge on the slidable member for engaging the bottom of a can, a connecting link pivotally interconnecting the upper end of the sliding member and the lower end of the bracket for moving the sliding member longitudinally of the pivotal member when the pivotal member is moved about its pivotal connection to the bracket thereby raising a can positioned on said ledge into contact with the punch members for puncturing a pair of spaced holes in the top of the can, and projecting means for engaging the side wall of a can when it has been punctured for disengaging the bottom of the can from the ledge thereby permitting removal of the can, the outer of said punch devices being adjustably attached to said arm wherein various sized cans may be punctured adjacent diametrically opposed points.

10. A can opening device comprising an elongated vertically disposed supporting bracket for attachment to a support, an elongated pivotal member attached to the upper end of said bracket and normally depending therefrom in coextensive angular relation, a laterally extending arm on said pivotal member, a pair of spaced depending punch members on said arm, a can holding member slidably mounted on said pivotal member below the punch members, a projecting ledge on the slidable member for engaging the bottom of a can, a connecting link pivotally interconnecting the upper end of the sliding member and the lower end of the bracket for moving the sliding member longitudinally of the pivotal member when the pivotal member is moved about its pivotal connection to the bracket thereby raising a can positioned on said ledge into contact with the punch members for puncturing a pair of spaced holes in the top of the can, and projecting means for engaging the side wall of a can when it has been punctured for disengaging the bottom of the can from the ledge thereby permitting removal of the can, said laterally extending arm being slidably and pivotally connected to said pivotal member for receiving cans of various lengths and pivoting to a collapsed condition alongside the front surface of the pivotal member, spring means normally urging said arm to a laterally extending position.

11. A can opening device comprising an elongated vertically disposed supporting bracket for attachment to a support, an elongated pivotal member attached to the upper end of said bracket and normally depending therefrom in coextensive angular relation, a laterally extending arm on said pivotal member, a pair of spaced depending punch members on said arm, a can holding member slidably mounted on said pivotal member below the punch members, a projecting ledge on the slidable member for engaging the bottom of a can, a connecting link pivotally interconnecting the upper end of the sliding member and the lower end of the bracket for moving the sliding member longitudinally of the pivotal member when the pivotal member is moved about its pivotal connection to the bracket thereby raising a can positioned on said ledge into contact with the punch members for puncturing a pair of spaced holes in the top of the can, and projecting means for engaging the side wall of a can when it has been punctured for disengaging the bottom of the can from the ledge thereby permitting removal of the can, the outer of said punch devices being adjustably attached to said arm wherein various sized cans may be punctured adjacent diametrically opposed points, said laterally extending arm being slidably and pivotally connected to said pivotal member for receiving cans of various lengths and pivoting to a collapsed condition alongside the front surface of the pivotal member, spring means normally urging said arm to a laterally extending position, a hook on said slidable can holding member for automatically engaging and holding the arm in collapsed position when the arm and pivotal member are moved inwardly in collapsed position and a manual latch on said bracket for holding

the pivotal member in collapsed position alongside the bracket, and resilient means urging the pivotal member outwardly thereby permitting the pivotal member and arm to move to their normal position upon release of the latch.

12. A can opening device comprising an elongated vertically disposed supporting bracket for attachment to a support, an elongated pivotal member attached to the upper end of said bracket and normally depending therefrom in coextensive angular relation, a laterally extending arm on said pivotal member, a pair of spaced depending punch members on said arm, a can holding member slidably mounted on said pivotal member below the punch members, a projecting ledge on the slidable member for engaging the bottom of a can, a connecting link pivotally interconnecting the upper end of the sliding member and the lower end of the bracket for moving the sliding member longitudinally of the pivotal member when the pivotal member is moved about its pivotal connection to the bracket thereby raising a can positioned on said ledge into contact with the punch members for puncturing a pair of spaced holes in the top of the can, and projecting means for engaging the side wall of a can when it has been punctured for disengaging the bottom of the can from the ledge thereby permitting removal of the can, said arm and punch members being rigidly connected to the upper end of said pivotal member. 25

13. A can opening device comprising an elongated vertically disposed supporting bracket for attachment to a support, an elongated pivotal member attached to the upper end of said bracket and normally depending therefrom in coextensive angular relation, a laterally extending arm on said pivotal member, a pair of spaced depending punch members on said arm, a can holding member slidably mounted on said pivotal member below the punch members, a projecting ledge on the slidable member for engaging the bottom of a can, a connecting link pivotally interconnecting the upper end of the sliding member and the lower end of the bracket for moving the sliding member longitudinally of the pivotal member when the pivotal member is moved about its pivotal connection to the bracket thereby raising a can positioned on said ledge into contact with the punch members for puncturing a pair of spaced holes in the top of the can, and projecting means for engaging the side wall of a can when it has been punctured for disengaging the bottom of the can from the ledge thereby permitting removal of the can, said projecting means including a pair of laterally extending legs for engaging the periphery of a can closely adjacent each side of the pivotal member.
